UNITED STATES PATENT OFFICE.

WILLIAM D. FORSYTH, OF YOUNGSTOWN, OHIO, ASSIGNOR, BY DIRECT AND MESNE ASSIGNMENTS, TO RAILWAY PRODUCTS CORPORATION, OF BUFFALO, NEW YORK, A CORPORATION OF NEW YORK.

DRAW-BAR YOKE.

1,188,433.

Specification of Letters Patent. Patented June 27, 1916.

Application filed August 28, 1912. Serial No. 717,506.

To all whom it may concern:

Be it known that I, WILLIAM D. FORSYTH, a citizen of the United States, residing at Youngstown, in the county of Mahoning 5 and State of Ohio, have invented new and useful Improvements in Draw-Bar Yokes, of which the following is a specification.

My invention relates to improvements in draw bar yokes and appliances therefor for attaching and detaching said yokes to and from the draft gear of the cars upon which they are used.

The principal objects of my invention are to provide a draw bar yoke made up of interchangeable parts of simple and cheap construction, preferably of metal forgings; said parts being capable of performing their respective functions wherever placed in said yoke, and said yoke as an entirety being capable of quick and cheap attachment and detachment to and from the draft gear of the cars upon which they are used, whether said cars be in transit or in the shops, and whether said yokes be attached or detached 25 to and from said draft gear as an original installation thereon, or from time to time for purposes of repair.

My invention consists of a draw bar yoke made up of several interchangeable parts 30 and the appliances for attaching and detaching said yokes to and from the draft gear on which they are to be used as herein-after more specifically set forth.

In the accompanying drawings forming part of this specification, Figure 1 is a side elevation of my improved draw bar yoke. Fig. 2 is an end view of Fig. 1 with the draw bar in section. Fig. 3 is a view of the end of the draw bar yoke, opposite the draw bar end, showing the draft sills of the car on which the draw bar is used. Fig. 4 shows a top plan view and edge view of the yoke side bar shown in Fig. 1. Fig. 5 shows an end view and a top plan view of the clevis or sleeve shown in Fig. 1. Fig. 6 shows a top plan view and edge view of a modified form of yoke side bars with the shoulders at the draw bar end notched in the edges of said bars. Fig. 7 is an end view and top plan view of clevises to be used with yoke side bars of the type shown in the several figures.

Like figures of reference refer to like parts throughout.

In the various figures, 1, 1, represent the 55 draft sills of the car.

2 represents yoke side bars, having at the draw bar end inwardly projecting shoulders at 3 and 4, and at the end opposite the draw bar end, a deeper inwardly projecting 60 shoulder at 5, which has an extension 6. At the draw bar end, yoke side bar has a perforation 7. Each extension 6 has a perforation 8.

9 is a draw bar which has shoulders at 10, 65 10, each corresponding in dimension and form with shoulder 4 of yoke side bar 2; said draw bar has a perforation 11.

12 is a collar or sleeve, rectangular in shape, which has hole 13 and is of sufficient 70 size to pass over the draw bar ends of yoke side bars 2, as shown in Figs. 1, 2 and 3.

14 is a pin of such size that it will pass through hole 13 of the collar 12, holes 7 of yoke side bars 2, 2, and hole 11 of draw bar 75 9. Said pin 14 has a hole 15 through which a cotter pin 16 may be passed.

12', Fig. 7, is a collar which passes over extensions 6, 6, of yoke side bars 2, 2, and is 80 provided with a perforation 17.

18 is a pin of such size that it will pass through hole 8 of each extension 6 and hole 17 of collar 12'. Said pin 18 has a hole 19 for the reception and retention of a cotter pin 20.

21, 21, are two spring seat plates which abut against shoulders 3 and 5, respectively, of yoke side bars 2. Upon said spring seat plates spiral spring 22 is mounted.

23 are bars which are removably bolted to 90 the lower flange of sills 1, 1, by nuts and bolts 24, 24 as shown in Figs. 1 and 3, to support the draw bar yoke thereon.

In Fig. 6, 2' is a modified yoke side bar in which the shoulder 3' is substituted for 95 the shoulder 3 of yoke bar 2, the shoulder 3' of yoke bar 2' being notched in the edge of yoke side bar 2, instead of being formed by an angle or bend therein. Said yoke side bar 2' has a shoulder 4', a shoulder 5', a 100 hole 7', and an abutment 6', having a hole 17'.

What I claim as my invention is:

1. A draw bar yoke comprising perfor-

2
rated yoke side bars each having a shoulder at each of their ends, and a shoulder intermediate their ends, and a perforated extension at one of their ends; perforated collars adapted to be mounted upon the ends of said side bars and the extensions thereof respectively, and removable pins passing through the perforations of said side bars, the extensions thereof, and said collars.

10 2. A draw bar yoke comprising a pair of yoke side bars, each having an end portion offset toward the other yoke side bar, the ends of said offset portions being bent toward each other, a draw bar having an end mounted between said offset portions and having shoulders engaging said bent ends, the ends of said yoke side bars opposite to said bent ends being bent toward each other and having extensions arranged substantially parallel with each other, a collar surrounding said offset portions and a second collar surrounding said extensions, said

collars being removable, a removable pin passing through the collar on said offset portions and said offset portions and said draw bar, another removable pin passing through said second collar and said extensions, and removable means for retaining said pins in place.

3. A draw bar yoke formed of two side bars, removable collars for the respective ends of said side bars, removable pins through said collars and said side bars, and a removable fastening for retaining said pins in place, each of said side bars being bent to form shoulders thereon located between its ends.

In testimony whereof I have hereunto set my hand in the presence of two subscribing witnesses.

WILLIAM D. FORSYTH.
